UNITED STATES PATENT OFFICE.

ALONZO SWEETLAND, OF TALMAGE, CALIFORNIA.

PROPELLER FOR VESSELS.

SPECIFICATION forming part of Letters Patent No. 637,181, dated November 14, 1899.

Application filed October 8, 1898. Serial No. 692,981. (No model.)

To all whom it may concern:

Be it known that I, ALONZO SWEETLAND, a citizen of the United States, residing at Talmage, in the county of Mendocino and State 5 of California, have invented certain new and useful Improvements in Propellers for Vessels, of which the following is a specification, reference being had therein to the accompanying drawings.

10 This invention relates to certain new and useful improvements in propellers for vessels.

The objects of my invention are to provide suitable pull-rods for paddles which will permit the paddles to change their angles to an 15 endless belt or chain, as when in passing around a sprocket-wheel or drum; to provide a suitable frame structure, a portion of which constitutes guides whereby a pair of endless 20 belts or chains are prevented from sagging, and to provide suitable paddle-rods with rollers for traveling upon the guides, whereby the chains or belts will run with less friction.

25 My invention relates also to details of construction hereinafter appearing, and particularly pointed out in the claim.

In the accompanying drawings, on which like reference-letters indicate corresponding parts, Figure 1 is a vertical side elevation of 30 a boat or vessel, showing my invention applied thereto. Fig. 2 is a partial plan view of the same, also showing my invention in plan applied thereto; Fig. 3, a detail view of a portion of the endless chain, showing my improved pull-rod connected therewith, as also 35 connected with one of the paddles near its upper edge, and also showing the rollers on the ends of two or more paddle-shafts; Fig. 4, a detail view showing a portion of the 40 frame structure and the manner in which it may be secured to the boat or vessel, as also a net device for preventing the paddles from becoming obstructed or injured.

The letter A represents a boat, which may 45 be of any size desired, to which is applied my invention, which consists of a frame structure bolted or secured to the sides of the boat by means of lag-screws or bolts B, as clearly shown in Fig. 4, or in any other suitable manner. This frame structure is composed of 50 suitable braces C, bed-plates D, and angle-

iron guides E and F, mounted upon and secured to said plates D. Near each end of these guides and between them is mounted a pair of sprocket-wheels G and a pair of 55 sprocket-wheels H, respectively, upon the respective shafts I and J, supported by the bearings K in the sides of the vessel. These shafts are long enough to extend a distance beyond the vessel on each side to readily permit of the reception of the sprocket-wheels, 60 as above described. A suitable motor-shaft L, carrying a sprocket-wheel M, also mounted in a bearing in a standard N, acts to transmit motion to one or both of the shafts I and J by 65 means of a sprocket-chain O, passing around a sprocket-driven wheel P on the shaft J. A pair of endless sprocket chains or belts pass around the sprocket-wheels H and G—that is, one of said endless sprocket-chains passes 70 around one set of the sprocket-wheels G and H and the other sprocket-chain passes around the other set of sprocket-wheels G and H, thus making a double set of chains running 75 parallel to each other. Referring now to my improved means for holding the paddles in position and for pulling them through the water and also the manner of connecting them with these endless chains, it will be seen in Fig. 3 that I have provided a pull-rod 80 bifurcated at each end. At its lower end its bifurcation is adapted to fit over one of the endless chains and is pivotally connected with one of the paddle shafts or rods b. The upper end of these bifurcated pull-rods is adapted 85 to engage with a lug or extension c, carried by a paddle d, near its upper edge, which paddle is hinged to the paddle-shaft by means of hinges e. The outer ends of said shafts also carry rollers which are adapted to roll 90 upon the angle-irons E and F, forming a portion of the frame structure.

As the sprocket-wheels or drums are rotated by means of any desired power mechanism within the boat, such as by an engine, (not 95 shown,) the endless chains, together with their paddles, are carried around and dip into the water, the level of which is shown by the line y y, and cause the boat to travel forward, it being understood that the paddles are traveling in the direction of the arrow, as shown in Fig. 1. Thus it will be seen that the rods a 100

can pull on the paddles and hold them in their most effective position while they are traveling through the water, and at the same time, being hinged to the paddle-rods and to the 5 paddles, they will permit the paddles to separate in passing around the outer portion of the sprocket-wheels or drums. There are a sufficient number of these paddles, so that they may act upon the water with enough 10 rapidity to prevent their churning the water into foam and also to reduce the amount of pressure on each paddle.

In order to protect the paddles from injury, I provide a strong lattice covering. (Indicated 15 by dotted lines *f* in Fig. 1 and also as clearly shown in Fig. 4 at *g*.)

In practice this invention has been found to be very efficient and as here constructed is durable and cheaply manufactured. In case 20 of a break or accident the parts may be readily supplied, so that undue delays in travel may thus be avoided. My improved paddles may travel in either direction around the sprocket-wheels or drums with equal facility, 25 so that the vessel or boat may travel either forward or backward, as desired.

Having thus fully described my invention,

what I claim as new, and desire to secure by Letters Patent, is—

In an improved propeller for vessels, the 30 combination with a pair of shafts, of one or more drums or sprocket-wheels mounted on each of said shafts, an endless chain or plate passing around said drums and driven thereby, a series of paddles hinged to said chain, 35 a lug or extension secured to each of said paddles near their outer edges, a pull-rod having each of its ends bifurcated, one of which ends is pivotally connected with one of said extensions and the other end of which extends 40 on each side of said chain, the rod in advance of said paddle, and adapted to extend through such lower end of the pull-rod and also extending through said chain, a roller mounted on the end of said rod, and guides between 45 the drums which also act as supports for said chain and as guideways for said rollers, all substantially as shown and described.

In testimony whereof I affix my signature in presence of two witnesses.

ALONZO SWEETLAND.
